Patented July 6, 1920.

FIG. 5.

FIG. 6.

FIG. 7.

INVENTOR.

BY Alexander McDougall,
Geo. Stevens.

ATTORNEY.

UNITED STATES PATENT OFFICE.

ALEXANDER McDougall, of Duluth, Minnesota.

VESSEL.

1,345,610.

Specification of Letters Patent.

Patented July 6, 1920.

Application filed July 29, 1918. Serial No. 247,100.

To all whom it may concern:

Be it known that I, ALEXANDER McDougall, a citizen of the United States, residing at Duluth, in the county of St. Louis and 5 State of Minnesota, have invented certain new and useful Improvements in Vessels, of which the following is a specification, reference being had therein to the accompanying drawing:

10 This invention consists of certain improvements in vessels, and relates particularly to a novel form of superstructures for vessels, used both on inland waterways, such as canals or the like, and on the open seas. 15 Vessels for such service must have sufficient depth of hull in proportion to their length and breadth to give proper longitudinal strength for seaworthiness, and which depth together with the ordinary fixed 20 superstructures such as cabins and pilot houses, results in a vessel impossible of navigation through canals spanned by low fixed bridges, as are in common use.

25 Sea-going vessels having removable superstructures for navigating under bridges are known in the art, and the principal object of my present invention is to provide auxiliary superstructures made adjustable upon the deck of the vessel to a certain predetermined height, for the safety of the crew 30 while thus navigating the vessel.

35 It is evident that when the main superstructures are lowered for operation in a canal, there are times intermediate of the bridges when certain elevated structures, say for the lights, whistle, smoke-stack and steering platform are essential, and these are the structures here particularly referred to.

40 Another object is to provide a form of superstructure which, when passing under a bridge, if left upright by mistake, will result in the least possible damage by its 45 engaging the bridge and whereby the tackle which holds the structure upright from the forward side will simply be broken and the structure prostrated automatically on the deck of the vessel with no damage except that to the tackle.

50 Other objects and advantages of the novel construction and arrangement of parts will appear in the further description of the invention.

Referring to the accompanying drawings forming part of this application and in

which like reference characters indicate like 55 parts:

Figure 1 is a side elevation of a vessel equipped with removable superstructures, and furnished with my improved auxiliary 60 collapsible superstructures.

Fig. 2 is a similar view of the vessel, showing only the foldable superstructures in use as would be employed when the vessel was navigating canals.

Fig. 3 is a top plan view of the vessel, 65 showing only the foldable superstructures folded flat upon the deck, and the other structure removed.

Fig. 4 is a side elevation of the Fig. 3.

Fig. 5 is an enlarged side elevation of the 70 navigator's foldable platform, illustrated in its upright position.

Fig. 6 is an enlarged side elevation of the auxiliary foldable smokestack illustrated in 75 an upright position.

Fig. 7 is an enlarged fragmental view of one leg of the foldable structures, illustrating one form of pivotally mounting same upon the deck of the vessel.

1 represents the hull of a vessel upon 80 which is mounted the after-cabin or deck house 2, and forward deck house 3. 4 represents the navigator's platform which, as here illustrated, is employed both while the vessel is being navigated in open waters, or 85 in canals between bridges, it being of the folding type of superstructures. This platform is pivotally mounted upon four angle iron legs 5, which are in turn pivotally mounted upon the deck 7 of the vessel. The 90 platform 4 may be surrounded by any desired form of removable railing 8, and is preferably provided with one or more guy lines 9 attached to the aft edge of the structures and to the deck of the vessel. The 95 platform 4 is rigged with a suitable block and tackle 10, which is connected to a fastening in the deck a suitable distance forward of the platform for raising same into position and holding it secure after being 100 raised. The ladder 11 is pivotally attached to the after edge of the platform and designed to raise and lower with the same. I have illustrated the legs 5 as being of angle iron and supported from the deck 7 by clips 105 12 of similar angle bar, but it is evident that various forms of construction might be resorted to without departing from the spirit

of the invention, as an example the platform frame and legs might be constructed of pipes suitably hinged together, and made to answer the purpose.

5 Upon the platform 4 or beneath it in a suitable pit indicated at 23, may be mounted any form of convenient steering gear or wheel which may be connected to the steering chains of the vessel in any desired 10 manner.

At 13, 14, 15, and 16 are illustrated the foldable forward mast, side lights, whistle and after mast respectively, these each comprise a central upright support indicated by 15 their respective numbers and two spaced flaring leg portions indicated at 17, and which give thwartship strength to each support.

The feet of the legs are pivotally supported upon the deck 7 of the vessel as illustrated in Fig. 7 or in any other practical manner and their upper ends are rigidly fixed to their respective central members.

To the after side of each central member 25 is attached a suitable stay 18 composed of rope, pipe or rod as preferred and of a proper length to maintain the member in a perpendicular position when raised and pulled taut by the tackle 19 which is attached to the forward side of each member 30 and leads to a suitable eye bolt or fastening in the deck.

The auxiliary smoke stack is represented at 20 and comprises six pivotally inverted 35 flat metal plates, the after one of which is, at its base, pivotally attached by a suitable hinge to the deck of the vessel as at 21.

This stack is of suitable height to elevate the smoke and gases above the heads of the 40 sailors and maintain sufficient draft in the boilers, and may be quickly lowered by being folded together toward the stern and lowered upon the deck as shown in Fig. 3, or readily raised again with the tackle 22, 45 provided for the purpose.

When the deck houses 2 and 3 are in place

on deck the auxiliary folding stack may remain upright and form the double stack necessary through the deck house 2 and thus become a coöperative part thereof.

In the case of a barge not having propelling power of its own, there may be a collapsible pivotal working platform such as herein disclosed upon both ends of the vessel and any other form of deck house dispensed with. Thus all of the superstructures of the vessels may be pivotally attached to the deck thereof and be raised and lowered alternately when navigating canals.

It is known that certain mooring devices such as bollards and capstans are constantly required upon the deck of the vessel and these preferably being permanently fixed thereon, provide an established height for clearance of the vessel when passing under 65 bridges, and in making the other superstructures of the vessel to be collapsible within such clearance is all that is necessary to make the vessel applicable to such navigation.

The necessity of the lights, whistle and navigating platform being considerably above the upper deck of the vessel is well known in the art, and I have herein provided simple and efficient means for such, 75 and method of manipulating same.

Having thus described my invention, what I claim and desire to secure by Letters Patent, is:

An auxiliary smoke stack for sea-going 80 canal boats comprising a plurality of metal plates pivotally united at their longer sides and one of the plates being pivotally attached to the deck of the boat whereby the stack may be collapsed and folded upon the 85 deck.

In testimony whereof I hereunto affix my signature in the presence of two witnesses.

ALEXANDER McDougall.
